WRENCH

Weston R. Smith, Jackson, Mich.

Application October 30, 1939, Serial No. 302,037

1 Claim. (Cl. 81—103)

The invention relates to a wrench and more especially to a pipe wrench of the Stillson type.

The primary object of the invention is the provision of a wrench of this character, wherein on relative adjustment of the jaws thereof, these can be positively locked against displacement and in this way assure a firm grip and holding of a piece of work.

Another object of the invention is the provision of a wrench of this character, wherein the movable jaw can be readily and quickly adjusted and adjustment may be had minutely, the movable and fixed jaws of the wrench being flexibly related to each other so as to assure the gripping of a piece of work.

A further object of the invention is the provision of a wrench of this character, wherein the locking of the movable jaw is had in a novel manner so that there is no liability of the loosening of the grip upon the work by the wrench in the use of the same.

A still further object of the invention is the provision of a wrench of this character, wherein adjustment is had from either side of the wrench and on adjustment both jaws of the wrench are normally held in parallel relation to each other, that is to say, the working faces thereof so that one jaw will not tip relative to the other jaw during adjustment, thereby enabling accurate adjustment to be had.

A still further object of the invention is the provision of a wrench of this character, which is simple in construction, thoroughly reliable and efficient in operation, convenient and easy of adjustment, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a fragmentary side elevation of a wrench constructed in accordance with the invention.

Figure 2 is a vertical transverse sectional view taken on the line 2—2 of Figure 1 looking in the direction of the arrows.

Figure 3 is a fragmentary vertical longitudinal sectional view through the wrench.

Similar reference characters indicate corresponding parts throughout the several views in the drawing.

Referring to the drawing in detail, A designates generally a portion of the wrench constructed in accordance with the invention and includes the work-engaging jaws 10 and 11, respectively, these having serrated work-contacting faces 12. The jaw 10 is at the inner end of a leverage handle 13 while the jaw 11 is formed with a feed rack or stem 14 at its outermost edge having ratchet teeth 15 while fitting the jaw 10 is a turnable eccentric 16 integral with a turning arbor 17 journaled in the side cheeks 18 fastened to a ratchet latch or ratchet toothed latching runner 19 coacting with the teeth of the rack 15 so that the jaw 11 can be latched in an adjusted relation to the jaw 10. The feed rack or stem 14 is slidably fitted between the cheeks 18 and the dog or runner 19 is fastened at 20 to these cheeks being counterseated at 21 in both cheeks.

The jaw 10 is formed with a fulcrum 22 making contact with the rack or stem 14. The jaw 10 also is formed with a shoulder 23 having fastened at 24 thereto a leaf spring 25 which has fastening to a guide collar or bail 26 slidably fitting the rack or stem 14. This spring 25 sustains normally the faces 12 of the jaws 10 and 11 in parallelism under adjustment of the said jaws relative to each other. The eccentric 16 functions on the turning thereof to bring the dog or runner 19 into and out of latching engagement with the teeth 15 of the rack or stem 14.

Mounted upon the dog or runner 19 is a spring glider 27 which rides the teeth 15 and functions to urge the said dog or runner 19 out of meshing engagement with the teeth 15 and also the fulcrum 22 in contact with the rack or stem 14. The spring 25 assures flexibility to the jaws 10 and 11 for the firm and positive gripping of a piece of work by the faces 12 of said jaws.

The arbor 17 at opposite ends thereof has fixed peripherally knurled turning knobs 28 and one of the latter has provided peripherally therein a segmental recess or notch 29 accommodating a stopping pin 30 fixed at 31 to the jaw 10. The coaction between the notch 29 and the pin 30 limits the turning movement of the eccentric either clockwise or counter-clockwise and brings the dog or runner 19 into latched engagement with the teeth 15 or out of latched engagement therewith on the rack or stem 14. The glider 27 is fixed by fasteners 32 to the dog or runner 19.

By reason of the construction of the wrench hereinbefore set forth flexibility is had between the jaws 10 and 11 and quick and easy adjustment of one jaw relative to the other can be had while accuracy in close adjustment will be

assured. The adjustment of the wrench can be had from either or both sides thereof. On the flexing of one jaw relative to the other of the wrench the fulcrum 22 plays upon the rack or stem 14 so a positive and firm grip by the faces 12 of the jaws 10 and 11 may be accomplished in the use of the wrench.

What is claimed is:

A wrench of the character described, comprising a handle having an enlarged outer end forming a jaw, a yoke straddling the enlarged end of the handle and having teeth on the inner looped end thereof, an eccentric connection between the yoke and the handle, means for operating said

5 eccentric, a movable jaw passing through said yoke and having teeth on its outer edge engaging the teeth in the yoke and provided with a lateral end forming a jaw parallel with the enlarged outer end of the handle, a fulcrum point carried by the enlarged end of the handle and engaging the inner edge of the movable jaw, a spring carried by the yoke for causing the fulcrum point of the handle to engage the edge of the jaw, a sleeve 10 slideable on the inner end of the movable jaw, and a leaf spring connecting said sleeve and the enlarged end of the handle.

WESTON R. SMITH.
